INFANT'S SHOE

Otto A. Hildebrand, St. Louis, Mo.

Application July 28, 1950, Serial No. 11,450

Term of patent 14 years

(Cl. D7—7)

To all whom it may concern:

Be it known that I, Otto A. Hildebrand, a citizen of the United States, residing in the city of St. Louis, State of Missouri, have invented a new, original, and ornamental Design for an Infant's Shoe, of which the following is a specification, reference being had to the accompanying drawing, forming part thereof.

Fig. 1 is a front perspective view of an infant's shoe, showing my new design;

Fig. 2 is a side elevational view, the opposite side presenting substantially the same appearance as the side shown;

Fig. 3 is a rear elevational view; and

Fig. 4 is a front elevational view.

I claim:

The ornamental design for an infant's shoe, as shown and described.

OTTO A. HILDEBRAND.
